FRED F. KOHN, OF NEW YORK, N. Y.

SHOE-BUCKLE HOLDER.

Application filed January 24, 1928. Serial No. 249,184.

This invention relates to shoe buckle holders, which constitute means secured to the upper edge of the shoe vamp with which buckles may be detachably connected and supported.

The invention primarily comprehends a buckle holder of the character set forth, which while rigidly maintaining the buckle in applied position, facilitates the engagement and disengagement of the same with relation to the holder.

The invention furthermore contemplates a shoe buckle holder of the class described which is extremely simple in its construction and mode of use, which is inexpensive to manufacture, and which is highly efficient in its purpose.

With the above recited and other objects in view, reference is had to the following description and accompanying drawings in which there is exhibited one example or embodiment of the invention, while the appended claim define the actual scope of the invention.

In the drawings—

Figure 1 is a sectional view through the device in applied position with the buckle attached, said section being taken approximately on the line 1—1 of Fig. 2;

Fig. 2 is a sectional plan view taken approximately on the line 2—2 of Fig. 1;

Fig. 3 is a front elevation of the holder detached from the shoe;

Fig. 4 is a side elevation thereof;

Fig. 5 is an enlarged fragmentary cross-sectional view similar to Fig. 2.

Referring to the drawings by characters of reference, the holder which is constructed from a single sheet of resilient material, is cut, bent and formed to provide a suitable base 10, which is of substantially U shape or channel shape in cross section and provided with anchoring prongs 11. The device is adapted to engage over the upper edge of the vamp portion A of the shoe. The holder further includes an upstanding buckle bar clamping element which is preferably upwardly and rearwardly inclined, and which element includes a bight portion 12 having side walls 13—13 which converge or incline

toward each other from the bight to the free edges. The free edges are provided with laterally extending flanges 14—14. The bight is joined to the base 10 by a shank 15 and at the juncture of the bight with the shank the free edges of the side walls are flared outwardly as at 16. The bight and side walls are formed with longitudinally spaced cut-away portions 17, which in addition to lightening the holder, increase the flexibility of the same. The confronting inner faces of the side walls 13 may further be provided with inwardly directed longitudinally spaced projections 18 to further insure the retention of the buckle bar B which is carried by the rear of the buckle C. In order to provide means whereby the buckle may be permanently attached to the holder, the flanges 14 are formed with apertures 19 for suitable fastening means, such as stitching.

From the foregoing it will thus be seen that a shoe buckle holder has been devised, which while rigidly supporting the buckle, facilitates the engagement of the buckle bar therewith and disengagement of the same therefrom.

What is claimed is:

A device for connecting a shoe buckle to a shoe comprising a member bent and formed from an inverted substantially T-shaped sheet of resilient material to provide a channel shaped base adapted to clampingly engage the upper edge of the shoe vamp and an upstanding channel shaped buckle bar clamping portion including a bight and side walls converging toward each other from the bight toward the free edges and laterally projecting flanges at the free edges of the side walls.
